UNITED STATES PATENT OFFICE.

JOSEF BRANDSTETTER, OF CHICAGO, ILLINOIS.

PHONOGRAPH STOP.

Application filed October 27, 1923. Serial No. 671,266.

To all whom it may concern:

Be it known that I, JOSEF BRANDSTETTER, citizen of the United States, residing at Chicago, in the county of Cook and State 5 of Illinois, have invented certain new and useful Improvements in a Phonograph Stop; and I do hereby declare the following to be a full, clear, and exact description of the invention, such as will enable others 10 skilled in the art to which it appertains to make and use the same.

My invention relates to a phonograph attachment for use with the class of phonographs in which the reproducer is carried 15 by a tone arm which swings over the record disk.

Generally speaking, my invention aims to provide an exceedingly simple, easily manipulated and inexpensive stop for this 20 purpose; also one which can readily be attached to previously completed or already installed phonographs, which will have the major portions of such a relatively low height as to be readily disposed below the 25 turntable and to be largely concealed by the turntable; and one which can easily be adjusted so as to hasten or retard the stop action according to the amount of lost play and the extent of bending of various parts 30 of the stop mechanism and of the phonograph portions operatively associated with the same.

More particularly, my invention provides a phonograph stop which can readily be 35 attached to a standard type of phonograph without requiring any alterations or machine work on the latter, which will have its trip arm operated directly by the swinging tone arm of the phonograph without 40 requiring the attaching of any auxiliary parts to this tone arm, which can easily be manipulated for setting it according to the effective length of the record, and which can readily be adjusted with a high degree 45 of accuracy as to the point at which it stops the record.

Furthermore, my invention provides a phonograph stop in which the movement of the trip arm when adjusting the latter also 50 tends to move the latching arm, in which the resulting movement causes the latching arm to exert a pressure on the brake arm, and in which the adjustment demanded by variations in sizes and shapes of the parts 55 and the assembly of the latter is afforded by an adjustable limit stop associated either

with the brake arm or with the latching arm. Still further and also more detailed objects will appear from the following specification and from the accompanying drawings, in which—

Fig. 1 is a fragmentary plan view of a phonograph, showing the tone arm and the reproducer as they appear to a person looking downward while standing behind the 60 phonograph, and showing the turntable and a record partly cut away to disclose the position of the stop embodying my invention, this stop being in its inoperative position as it appears during the playing of the 65 record.

Fig. 2 is an enlarged plan view of the same stop, showing this as it appears when the latch has been released so as to permit the spring to set the brake and stop the 70 turntable.

Fig. 3 is an enlarged and vertical section taken through Fig. 2 along the line 3—3 of that figure, with portions broken away to show the relative disposition of various 80 parts when the latch has been released and the brake arm is in its operative position.

Fig. 4 is a similar view taken when the latch is set so as to hold the brake arm in its inoperative position.

Fig. 5 is a somewhat diagrammatic elevation of parts of the same embodiment showing the operation of the adjustment and the setting of the stop according to the 90 length of the record.

Fig. 6 is a similar view showing another arrangement of the adjustment, namely one in which the adjustable limiting member directly engages the latching lever.

In accomplishing the purposes of my invention according to the illustrated embodiment, I provide as a supporting base a relatively thin horizontal plate 1 and a brake arm 2 secured to this base plate 2 by a vertical pivot pin 3 and moving in a horizontal plane close to the top of the base plate. This brake arm has a handle 4 projecting beyond the normally outward edge of the base plate. It also desirably has means engaging a portion of the base plate 105 to limit the pivotal movement of the brake arm in one direction, such as a downwardly turned finger 3 moving in a slot 6 in the base plate and engaging one end of the slot when the brake arm is moved in that direction by a tension spring 7 interposed between the brake arm and a post 8 fastened 110

to the base plate. The brake arm also carries a brake 9 of leather or the like disposed for engaging the interior of the usual downwardly turned flange 10 on the turntable 11 of the phonograph.

Pivoted to the base plate on a horizontal axis, such as that afforded by a pin 12, is a bell-crank lever, comprising a latching arm 13 (which extends close to the top of the base plate) and a riser arm 14. The latching arm has portions thereof continuously underhanging the brake arm 2, and to permit of this while having the brake arm close to the top of the base plate, I provide the base plate with a recess formation, such as a slot 15 into which this portion of the latching arm depends. Furthermore, this latching arm has an offset in the same so as to afford an upper face 16 engaged by the 10 brake arm when the latch is released and the brake is operative, and a relatively lower upper face 17 engaged by the brake arm when the latch is set so as to hold the brake inoperative, these two face portions 16 and 15 20 being joined by a shoulder 18 which engages an edge portion 19 of the brake arm when the latch is set. To effect the setting of the latch, the handle 4 is manually moved in a direction which is counterclockwise in 25 Figs. 1 and 2 so as to slide the brake arm from the position of Fig. 3 to that of Fig. 4, whereupon the latching arm is swung upwards as shown in Fig. 4 through the operation of a spring 20 which continuously 30 tends to swing the bell-crank lever in that direction.

The riser arm 14 carries an upward extension in the form of a trip arm 21 which is pivoted to the riser arm through a friction 40 joint 22 and which extends upwardly into the path of the tone arm 23 of the phonograph, so that (with the stop mounted as in Fig. 1) the movement of the tone arm during the playing of the record will cause this tone arm to engage the trip arm, thereby 45 moving the bell-crank lever against the resistance of the spring 20 and releasing the latch so that the spring 7 can set the brake.

In setting the stop for effective use with 50 any particular record 24, the trip arm is first swung far out of its operative position after the manner shown in dotted lines in Fig. 5, this being done while the brake is in its operative position. The tone arm is then 55 swung over the record and stopped with the needle 26 engaging the innermost groove of the record, after which the trip arm is swung up against the tone arm as shown in full lines in Fig. 5. As this is done when the 60 latch is in its released position, the resulting setting should correspond to the desired stop position if there were no lost motion in any parts and no springing of any parts, but in practice these last named occurrences 65 may make a difference of several revolutions

in the record as to the actual time and point of the stopping. This is true partly because there may be lost motion in the mounting of the tone arm and of the reproducer, partly because of the difficulty of accurately adjusting any friction joint, partly because of the springing of various parts of the stop, and also because of possible variations in the exact size and assembly of the component parts of my stop.

To compensate for such variations in the effective point of stopping, I provide adjustable means for limiting the swinging movement of the latching arm during the above described setting of the stop, and desirably provide this adjustment so that it operates through the brake arm and also serves to hold the latter continuously in a position close to the latching arm. For this purpose, I preferably mount upon the base plate 1 an adjustable member 26 made of resilient metal and presenting a finger 27 which overhangs the brake arm 2. This member 26 has one end rigidly fastened to the base plate by a screw 28, while a screw 29 extends into the base plate through a medial portion of this adjusting member so that the limit finger 27 can be bent downwards more or less according to the tightening or loosening of this screw 29.

In operating my stop, starting with the trip arm in the position shown in dotted lines in Fig. 5, the tone arm is so disposed that the needle of the reproducer engages the portion of the record groove at which it is desired to stop the needle. When the trip arm 21 is then swung against the tone arm as shown in full lines in Fig. 5, the friction of the joint 22 will tend to cause this movement of the trip arm to move the entire bell-crank or detent lever bodily. In doing so, the latching arm 13 of the lever raises the brake arm 2 until this brake arm is stopped by engagement with the limit finger 27. When thus stopped, the brake arm in turn acts as a stop for the latching arm so that the latter can not be swung upward farther, and the bell-crank lever then remains stopped as a whole while the trip arm 21 may move on further so as to take up any lost motion in the tone arm and reproducer mountings. As soon as the finger which trips the trip arm 21 against the tone arm is released, the resiliency of the brake arm and of the limit finger, both acting in opposition to the lifting tendency of the spring 20, return the bell crank lever to the position shown in Fig. 3 with the trip arm. At the same time, the tone arm and reproducer will snap back to their former positions. The trip arm 21 then extends at an angle to the latching arm which angle has been determined by the adjusted position of the limit finger. Consequently, by turning the screw 29 so as to adjust the position of this finger, I can vary

the effective angle between the trip finger and the latching member so as to compensate for the characteristics which would otherwise make the stop act either too soon or too late.

In practice I have found that even with the parts made of relatively thin stock and with only a moderate care employed in assembling the parts, the adjustment provided in this manner is such that I can readily cause my appliance to stop the needle within a small fraction of a single rotation of the record from the point on the groove at which the reproducer needle was placed when setting the stop.

To keep the latching arm of the detent lever close to the edge of the turntable so as to permit my stop to be used in phonographs where the space behind the turntable is quite limited, I desirably curve this arm concentrically with the turntable after the manner shown in Fig. 2 and correspondingly curve the slot entered by the free end portion of this arm so as to guide that portion. I also desirably form the shoulder portion 19 on the brake arm so that this shoulder will be radial of the said curvature when the brake arm is latched.

However, I do not wish to be limited to these or other details of the construction and arrangement here disclosed, it being obvious that the same might be modified in many ways without departing either from the spirit of my invention or from the appended claims. For example, instead of having the limit member (here shown as the finger 27) act on the latching arm through the intermediary of the brake arm, I can dispose this limit member so that it will engage the latching arm directly, after the manner of Fig. 6. However, I preferably employ the general arrangement of Figs. 1 to 4 so that the limit finger will aid in holding the brake arm close to the latching arm, thereby permitting me to use a brake arm made of thin and somewhat resilient material while permitting ample clearance between the top of the brake arm and the limit finger for avoiding friction while the brake is being released.

In either case it will be obvious that by using a flat base plate and a brake arm swinging closely over it, I can secure an assembly of such a low height as to find room for it under the turntable of a standard phonograph, while the use of a detent member moving in a vertical plane permits the trip arm to extend directly into the path of the tone arm, such a detent member being cheaply manufactured in the shape of a bell-crank lever having offset face and shoulder portions as above described. Also, since the top of the base plate 1 will engage the latching arm of the detent lever to limit the movement of the latter in its releasing

direction, I secure my said advantages by adjusting the effective distance between the two limit stops for the latching or detent member.

I claim as my invention:—

1. A phonograph stop comprising a supporting member, a spring-urged brake arm and a latching lever pivoted to the supporting member on relatively transverse axes and so arranged that the brake arm limits the movement of the latching lever in one direction, and a trip arm connected to the latching lever by a friction joint and so positioned that it will move the latching lever in the said direction when the trip arm is moved against the tone arm of the phonograph during the setting of the stop.

2. In a phonograph stop, a brake arm pivoted for movement in a horizontal plane, and a detent member pivoted for movement in a vertical plane, the detent member having an arm disposed in the path of the tone arm of the phonograph and having another arm disposed for latching the brake arm, the said other arm being curved concentric with the pivoting axis of the brake arm.

3. In a phonograph stop, a brake arm pivoted for movement in a horizontal plane, and a detent member pivoted for movement in a vertical plane, the detent member having one arm disposed in the path of the tone arm of the phonograph and having another arm disposed for latching the brake arm, the said other arm being curved concentric with the pivoting axis of the brake arm, the portion of the brake arm which is engaged by the said other arm of the detent member being radial of the said pivoting axis.

4. In a phonograph stop, a brake arm pivoted for movement in a horizontal plane, and a detent member pivoted for movement in a vertical plane, the detent member having an arm disposed in the path of the tone arm of the phonograph and having another arm disposed for latching the brake arm, and a support to which the brake arm and detent member are pivoted, the support having a base provided with a slot in which a part of the said other arm of the detent member moves.

5. In a phonograph stop, a brake arm pivoted for movement in a horizontal plane, and a detent member pivoted for movement in a vertical plane, the detent member having an arm disposed in the path of the tone arm of the phonograph and having another arm disposed for latching the brake arm, and a support to which the brake arm and detent member are pivoted, the support having a base provided with a slot in which a part of the said other arm of the detent member moves and having a portion adapted to engage the said other arm to limit the movement of the detent member in one direction.

6. A phonograph stop comprising a substantially horizontal base, a detent arm pivoted thereto on a horizontal axis and having a portion adapted to rest upon the top of 5 the base and a continuation portion of lesser height, a brake arm pivoted to the base on a vertical axis and having its lower face substantially in the plane of the upper edge of the first named detent arm portion when 10 this portion is resting on the top of the base, the juncture of the said two arm portions affording a shoulder for engaging the brake arm when the detent arm is raised off its said resting disposition, a spring urging 15 the brake arm toward the pivot of the detent arm, a second spring continuously tending to lift the detent arm and also tending to lift the brake arm when the brake is set, and means for limiting the lifting of the 20 brake arm.

7. A phonograph stop as per claim 6, in which the last named means comprise a limit member overhanging the brake arm and adjustable as to its height above the 25 portion of the base below the brake arm.

8. A stop for a phonograph, comprising a brake arm pivoted for movement in a horizontal plane, a spring continuously tending to move the brake arm to its braking 30 position, a detent lever pivoted for movement in a vertical plane and adapted to hold the brake arm in an inoperative position, and a trip arm pivoted to the detent lever by a friction joint and disposed in the 35 path of the tone arm of the phonograph; the brake arm being arranged to swing over an arm of the detent lever when the brake is set, so that the engagement of the detent lever with the brake arm will prevent the 40 detent lever from moving in one direction about its pivotal mounting during the adjusting of the trip arm about the friction joint.

9. A stop for a phonograph, comprising 45 a brake arm pivoted for movement in a horizontal plane, a spring continuously tending to move the brake arm to its braking position, a detent lever pivoted for movement in a vertical plane and having one arm adapted to hold the brake arm in an inoperative position, and a trip arm pivoted to the detent lever by a friction joint and disposed in the path of the tone arm of the phonograph, the brake arm being disposed for stopping the pivotal movement of the other arm of the detent lever towards the 50 tone arm.

10. A stop for a phonograph, comprising 55 a brake arm pivoted for movement in a horizontal plane, a spring continuously tending to move the brake arm to its braking position, a detent lever pivoted for movement in a vertical plane and adapted to hold the brake arm in an inoperative position, and a trip arm pivoted to the detent lever by a 60

friction joint and disposed in the path of the tone arm of the phonograph, the detent lever having a portion underhanging the brake arm when the brake is latched in its inoperative position and having another portion underhanging the brake arm when the brake is set. 70

11. A stop for a phonograph, comprising a brake arm pivoted for movement in a horizontal plane, a spring continuously tending 75 to move the brake arm to its braking position, a detent lever pivoted for movement in a vertical plane and adapted to hold the brake arm in an inoperative position, and a trip arm pivoted to the detent lever by a friction joint and disposed in the path of the tone arm of the phonograph, the brake arm being disposed for stopping the pivotal movement of the detent lever in one direction, a spring continuously tending to move 80 the detent arm in the said direction, and a stop for limiting the lifting of the brake arm by the detent lever. 85

12. A stop for a phonograph, comprising a brake arm pivoted for movement in a horizontal plane, a spring continuously tending to move the brake arm to its braking position, a latching lever pivoted for movement in a vertical plane and adapted to hold the brake arm in an inoperative position, and a trip arm pivoted to the latching lever by a friction joint and disposed in the path of the tone arm of the phonograph, the brake arm being disposed for stopping the pivotal movement of the latching lever in one direction, and a pair of stops for limiting the movement of the detent arm in respectively opposite directions. 95 100

13. A stop for a phonograph, comprising a brake arm pivoted for movement in a horizontal plane, a spring continuously tending to move the brake arm to its braking position, a latching lever pivoted for movement in a vertical plane and adapted to hold the brake arm in an inoperative position, and a trip arm pivoted to the latching lever by a friction joint and disposed in the path of the tone arm of the phonograph, the brake arm being disposed for stopping the pivotal movement of the latching lever in one direction, a pair of stops for limiting the movement of the latching lever in respectively opposite directions, and means for adjusting the effective distance between the stops. 115 120

14. A stop for a phonograph, comprising a brake arm pivoted for movement in a horizontal plane, a spring continuously tending to move the brake arm to its braking position, a latching lever pivoted for movement in a vertical plane and adapted to hold the brake arm in an inoperative position, and a trip arm pivoted to the latching lever by a friction joint and disposed in the path of the tone arm of the phonograph, 125 130

the latching lever having a portion underhanging the brake arm when the brake is latched in its inoperative position and having another portion underhanging the brake 5 arm when the brake is set, the juncture of the said two detent arm portions forming a shoulder for engaging the brake arm.

15. A phonograph stop comprising as one member a spring-actuated pivoted brake 10 arm, and as another member a lever having a latching arm underhanging the brake arm; and a trip arm mounted on the lever and disposed in the path of the tone arm of the phonograph, the trip arm being adjust-

able in position with respect to the latching 20 arm and being adapted to be moved against the said tone arm to adjust the stop, the arrangement being such that the said movement of the trip arm against the tone arm also moves the said lever in one direction; 25 and adjustable means associated with one of the first named two members for limiting the movement of the detent lever in the said direction.

Signed at Chicago, Illinois, Oct. 20th, 30
1923.
